UNITED STATES PATENT OFFICE.

JOSEPH EDWARD O'DONNELL, OF CAMDEN, NEW JERSEY.

TUBE-BENDING MACHINE.

SPECIFICATION forming part of Letters Patent No. 727,676, dated May 12, 1903.

Application filed October 9, 1902. Serial No. 126,571. (No model.)

To all whom it may concern:

Be it known that I, JOSEPH EDWARD O'DONNELL, a citizen of the United States, residing at Camden, county of Camden, and State of New Jersey, have invented a certain new and useful Improvement in Tube-Bending Machines, of which the following is a specification.

My invention relates to a new and useful improvement in tube-bending machines, and has for its object to provide a machine of this description by which tubes can be bent in different shapes without flattening said tubes in bending.

With this end in view the invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a plan view of the machine; Fig. 2, a longitudinal sectional view; Fig. 3, an end view of the machine; Fig. 4, a perspective view of the stock and its templet adapted to be attached thereto; Fig. 5, a perspective view of the adjustable chock.

A represents the bed-plate of the machine, which may be supported in any suitable manner. This bed-plate is formed as a segment of a circle and around its periphery is provided with cogs B.

C represents the center upon which the segment is struck.

D is a block secured rigidly to the upper surface of the bed-plate.

E represents the templet, adapted to be secured to the block around which the tube is to be bent. This templet is made in the form of a quarter-circle struck from the center C and in its curved periphery is formed a groove E', in which the tube is adapted to lie while being bent. The templet is made removable from the block for the purpose of securing to the block templets of different sizes, and it may be secured to the block in any convenient manner, so as to be readily removable; but that shown in the drawings consists of

forming upon the templet a tongue E², and the block D is formed angular where the templet fits upon the same, and the templet is cut out V shape to fit upon this angular portion. The tongue E² enters a groove formed in each surface of the block, and then double dovetail pins or wedges F are forced downward through the tongue, dovetail grooves being formed in the templet and also in the block in which fit the double dovetail pins or wedges F.

G is a lever which is pivoted at its inner end to the block D at the point C by means of the bolt G'. Thus when the lever G swings upon its pivot it will swing concentric with the periphery of the templet E and also with the periphery of the bed-plate A. This lever G is formed in two parts or rather is forked, one prong of the fork passing above the overhanging portion of the block D and the other prong of the fork passing underneath said overhanging portion, the bolt G' passing through both prongs. The two prongs of the lever G are joined together at the outer end by means of the housing G², and each of the prongs of the lever is slotted, as indicated at G³, and in these slots is adapted to slide the forked slide H. Between the ends of the prongs of this forked slide is pivoted the stock I of the bending-segment J, and this bending-segment is formed identical with the templet E and has a groove J' formed in its periphery in which the tube lies while being bent. This bending-segment is secured to its stock I in the same manner as the templet E is secured to the block D. A tongue J² protrudes into a groove formed in the stock, and double dovetail pins or wedges J³ serve to bind the two together. The stock I is pivoted to the prongs of the slide H by means of a bolt I', which passes through both of the prongs and also through the stock.

K is a screw-threaded rod swiveled at one end in the slide H and threaded through the housing G² of the lever G. This screw-threaded rod K is longitudinally grooved, as indicated at K' in Fig. 1, and located upon this screw-threaded rod, within the housing G², is a beveled wheel L, which is not threaded upon the rod, but is connected to said rod by means of a key entering the groove K', so that the rod may turn by the gear L to allow

the rod longitudinal movement relative to said gear.

M is a beveled gear-wheel in mesh with the gear-wheel L, and this beveled wheel M is secured on the lower end of an upright shaft M', journaled in the housing, and on the upper end of this shaft is secured a hand-wheel M² for the purpose of turning the gear-wheel M. Thus by rotating the hand-wheel M² motion will be communicated to the gear L, which will in turn revolve the screw-threaded rod K, and this rod being threaded in the housing will move the slide H, and consequently the bending-segment J, toward or away from the templet E, according to which direction the hand-wheel M² is revolved.

For the purpose of revolving the bending-segment J around the templet E, I journal through the housing G² an upright shaft N, upon the lower end of which is secured a gear O, which is in mesh with the cogs B upon the periphery of the bed-plate A. The upper end of this upright shaft N carries a worm-wheel P, which is in mesh with the worm Q, secured upon the end of a horizontal shaft R, which is arranged parallel with the lever G and directly above the same, it being journaled at its outer end in a standard S, arising from the lever G, and at its inner end it is journaled to a bearing S', pivoted to the block D at the point C. Upon the inner end of the shaft R is secured a beveled wheel R', which is in mesh with an idle beveled wheel T, journaled upon an upright stud in the block D at the center C.

U is a beveled wheel, also in mesh with the beveled wheel T, which is secured upon the end of a shaft U', journaled in the block D, and this shaft U' is the power-shaft, which is adapted to be rotated by any suitable source of power. Thus it will be seen that by rotating the shaft U' motion will be communicated to the shaft R, which through the worm-wheel and gear O will cause the lever D, and consequently the bending-block J, to travel in a circle concentric with the center C.

V is a chock which is adapted to hold the tube in position while it is being bent, and this chock is made in two parts, so that liners 50 may be placed between the parts, if necessary, to accommodate larger-size tubes. An upright bolt V' passes through the chock and serves to secure it to the bed-plate, and this chock rests upon ratchet-bars W, secured to the bed-plate, and the chocks are provided with pawls W', adapted to engage the ratchet-teeth of the ratchet-bars W. So to adjust the chock it is only necessary to loosen the bolt V', when the chock may be slid to any position desired and will be held against any retrograde movement by means of the pawls W', even if the bolt V' does not serve to hold the chock sufficiently.

In operation the machine is as follows: In inserting a straight tube in the machine the bending-lever G will be placed in the position shown in Fig. 1 and the tube to be bent

will then be inserted between the templet and the bending-segment. The chock V will then be forced up tightly against the tube, and then by rotating the hand-wheel M² in the proper direction the bending-segment J will be forced into tight contact with the tube, and then by communicating power to the shaft U' the gear O will be caused to revolve, 75 and it being in mesh with the cogs B will cause the lever G, and consequently the slide H and bending-wheel J, to travel in the direction of the arrow shown in Fig. 1, and when these parts have reached a position at 80 right angles to the position shown in Fig. 1 a right-angle bend will be formed in the tube. The opening formed by the two grooves E' and J' in the templet and bending-segment, respectively, when brought together will not 85 form a true circle; but the horizontal diameter will be larger than the vertical diameter. Thus as the tube is being bent the bending-segment will not contact the tube upon the back, and this will counteract the tendency of 90 the tube to flatten as it is being bent. After the tube is bent it is very easily removed or adjusted for further bending by revolving the hand-wheel M² so as to back the bending-segment away from its contact with the tube. 95 When it is desired to bend different-size tubes, the templet E and bending-segment J may be easily removed from the block D and stock I and other size parts substituted.

The principal advantage of my invention 100 is the adjustability of the bending-segment, as it allows for the manipulation of the tube, so that almost any curve can be given to the same. In fact, it can be bent in the form of a circle, if necessary.

Another advantage of my invention is the simplicity of the same, and by means of the few parts employed the same is made very durable.

Of course it is obvious that all of the pivotal parts of the machine could be, if desired, fitted with either roller or ball bearings to reduce the friction.

I do not wish to be limited to the exact construction here shown, as slight modifications 115 could be made without departing from the spirit of my invention.

Having thus fully described my invention, what I claim as new and useful is—

1. In a machine of the character described, 120 a segmental bed-plate, a block secured rigidly to said bed-plate, a segmental templet removably secured to said block, a bending-lever pivoted to said block, the periphery of the templet being concentric with said pivotal point, longitudinal guideways formed in the bending-lever, a forked slide adapted to be guided in said guideways, a stock journaled between the two prongs of said forked slide, a bending-segment removably secured 125 to said stock, said bending-segment being of the same radius as the templet, grooves formed in the periphery of both the templet and the bending-segment, said grooves so formed that 130

the bending-segment will not contact the tube upon its horizontal diameter, a screw-threaded rod swiveled in the forked slide and threaded through the outer end of the bending-lever, 5 a beveled gear-wheel feathered upon said screw-threaded rod, a beveled gear-wheel in mesh with the first-named gear-wheel, a hand-wheel for turning the last-named gear-wheel, an adjustable chock arranged upon the bed-plate, and means for revolving the bending-lever, as and for the purpose set forth.

2. In combination in a machine of the character described, a segmental bed-plate, cog-teeth formed upon the periphery of said bed-plate, 15 a block secured rigidly to the bed-plate, a segmental templet removably secured to the block, a bending-lever pivoted to the block, the periphery of the templet being concentric with said pivotal point, longitudinal guide-ways formed in the bending-lever, a slide fitted to slide in said guideways, a bending-segment journaled in said slide, grooves formed in the periphery of the templet and the bending-segment, means for causing said

bending-segment to travel toward and away 25 from the templet, a gear-wheel in mesh with the cogs upon the periphery of the bed-plate, an upright shaft to which said gear-wheel is secured, said shaft being journaled in the outer end of the bending-lever, a worm-wheel 30 secured to the upper end of said shaft, a horizontal shaft, a worm in mesh with the worm-wheel and secured on the outer end of the horizontal shaft, said shaft being journaled at the outer end to the bending-lever, 35 means for revolving said horizontal shaft so as to cause the bending-lever to turn upon its pivotal point, and an adjustable chock arranged upon the bed-plate, as and for the purpose specified.

In testimony whereof I have hereunto affixed my signature in the presence of two subscribing witnesses.

J. EDWARD O'DONNELL.
